US00D501846S

(12) **United States Design Patent** (10) Patent No.: **US D501,846 S**
De Saulles (45) Date of Patent: **** Feb. 15, 2005**

(54) **ALPHANUMERIC INPUT DEVICE WITH COVER**

(75) Inventor: **Stephen De Saulles**, London (GB)

(73) Assignee: **Patientline plc**, Slough (GB)

(**) Term: **14 Years**

(21) Appl. No.: **29/148,277**

(22) Filed: **Sep. 15, 2001**

(30) **Foreign Application Priority Data**

Mar. 16, 2001 (GB) 2100364

(51) **LOC (7) Cl. 14-03**

(52) **U.S. Cl. D14/218**

(58) **Field of Search** D14/174, 217, D14/218, 137-139, 151, 191-193, 124, 299, 167-168; D13/168, 162-164; D21/512-517, 566; D10/104, 106; 455/352-355, 151.1-151.4; 348/114, 734
